PERFORATING MACHINE

Erwin A. Gubisch, Chicago, Ill., assignor to Teletype Corporation, Chicago, Ill., a corporation of Delaware

Application March 1, 1944, Serial No. 524,605

9 Claims. (Cl. 164—113)

The present invention pertains to perforating machines and more particularly to apparatus for preparing perforated tape for telegraph signaling.

In operating telegraph tape perforating equipment manually by key levers, especially machines such as the Wheatstone perforator, there sometimes occurs the tendency of punch interponents, which have been selected as designating some code combination, moving downwardly due to the operator removing a finger from the keyboard too quickly, with the result that when the punching mechanism moves to operate the punches through the selected punch interponents the interponents which have moved downwardly will not operate their respective punches and therefore a blank code combination will be perforated in the tape.

Accordingly, it is the principal object of the present invention to prevent occurrence of the possible difficulty previously encountered and for assuring proper and correct perforation of the control strip for the depressed key lever.

The apparatus for the attainment of the above and other objects of the invention comprises in general spring urged pawls which move into a position under lugs on the punch interponents when the interponents move to their raised or selected position, thus preventing a downward movement of the interponents during the major portion of the punch hammer stroke. A pair of balls are provided which are actuated during the latter portion of the punch hammer stroke to cause an outward movement of the spring urged pawls, thus releasing them from under the lugs of the punch interponents to allow the punch interponents to return to their normal downward position.

The present invention has been disclosed as being used in combination with a standard Wheatstone perforator such as that substantially disclosed and described in U. S. Patent 1,085,985, issued to Edward E. Kleinschmidt on February 3, 1914, or in Bulletin No. 125, issued in August, 1937, by the Teletype Corporation of Chicago, Illinois. It should be noted, however, that the present device utilizes more links of a flexible nature than the perforator referred to above. However, it is to be understood that the use of the present invention is not limited to operation with a Wheatstone perforator but may be used with any tape perforating mechanism wherein a similar problem occurs.

A more complete understanding of the invention may be had from the following description

taken in connection with the accompanying drawings, in which:

Fig. 1 is a plan view of a Wheatstone perforator embodying the invention, with a section of the cover plate broken away;

Fig. 2 is a sectional view taken approximately on the line 2—2 of Fig. 1;

Fig. 3 is an enlarged view of the mechanism embodying the invention, as shown in Fig. 2;

Fig. 4 discloses an operational view of the apparatus embodying the invention showing its operated and released positions;

Fig. 5 is a plan view of the upper part of the apparatus as shown in Fig. 1 with the top mechanism removed;

Fig. 6 is an elevational view partly broken away showing the rear part of the Wheatstone perforator; and

Fig. 7 is a perspective view partly broken away, showing a special device to insure that the electrical contacts for operating the punch operating solenoid will be kept closed for a length of time sufficient for proper operation of the perforator.

The Wheatstone perforator, which is fully disclosed in the above-mentioned patent and bulletin, comprises a bank of key levers 11, the keys of which are provided with the characters of a universal keyboard and which may be manually operated by an operator preparing a perforated tape. The key levers 11 are fulcrumed about a transverse bar 12. Secured beneath each of the key levers 11 and secured thereto by means of a connecting member 13 are a series of notched code bars 14, one corresponding to each of the key levers 11, and having notches on their lower surface in accordance with the code combination for that particular symbol designated by the key. The code bars 14 are all fulcrumed on a transverse bar 15. The code bars 14 and their associated key levers 11 are held in a normal or unselected position by means of springs 17, one individual to each code bar. The upward movement of the forward end of the key levers 11 caused by the spring 17 is limited by a transverse leather stop 18 which is secured within the top frame at the front of the perforating apparatus, and overlies all of the key levers. A stop 19 is likewise provided to limit the downward movement of the code bars 14 and also the key levers 11 when depressed by an operator during the operation of the perforating equipment.

Upon the depression of any key, its corresponding key lever 11 and notched code bar 14 move downwardly, the specific contour of the lower edge of the code bar causing certain of

the transverse T-levers 21 to be depressed. Each T-lever 21 has connected thereto a rearwardly extending lever 22 which is connected at its rearward end to a punch interponent linking arm 23. The linking levers 22 are also fulcrumed about the transverse bar 16 and are provided with individual springs 24 located between the fulcrum point and the point of connection to the interponent links 23 thereby insuring that the levers will be pivoted about fulcrum 16 so as to retain the forward end of the levers 22 and the T-levers 21 connected thereto in their normal or upward position.

One of the T-levers 21 functions as a universal bar which will be depressed upon the operation of any one of the key levers 11. Such operation is provided by the notching of the underside of each of the code bars 14 in such a manner that the portion overlying the universal T-lever 21 will cause it to be depressed. The purpose of this universal T-lever 21, which has a rearwardly extending lever 22 which is not connected to a punch interponent link 23 but instead to a lever 26 which controls the opening and closing of an electrical contact for operating a solenoid, will be described later.

The present equipment is provided with twenty of the T-levers 21 each having a rearwardly extending lever 22 connected thereto. However, as previously mentioned, only nineteen of these levers are connected to the punch interponent links 23, the twentieth lever being connected to lever 26 which operates an electrical contact in the solenoid circuit.

Nineteen punch interponents 27 are provided which are connected to the links 23 by adjustable rods 28. The interponent levers 27 are arranged in two rows the forward row consisting of ten levers which do not extend to such a height as the back row of nine levers. Adjacent to each of the upper ends of the interponent levers 27 is a punch 29. Inasmuch as there are nineteen interponents provided there are likewise nineteen punches, one individual to each interponent. It is to be understood, however, that the number of punches and interponents may vary depending on the type of code being perforated. The punches 29 are arranged in an upper and a lower tier, the lower tier cooperating with the upper end of the punch interponents in the forward row composed of ten in number, and the upper tier of punches cooperating with the second row of nine punch interponents which extend above the interponents in the forward row. A special intermediate set of punches 30 is provided for perforating the tape feed perforations in the tape.

In operation, the operator depresses a key lever 11 resulting in the downward pivoting of the corresponding code bar 14. Depending on the notches in the lower edge of the code bar, certain of the T-levers 21 will be depressed which results in a corresponding depression or pivoting movement about the fulcrum 16 of the rearwardly extending levers 22 secured to the T-levers 21. The downward movement of the levers 22 which is a clockwise rotation thereof, as viewed in Fig. 2, results in certain of the punch interponents 27 being raised, through the links 23 and the adjustable bars 28, so that their upper ends are adjacent to a corresponding punch 29.

Referring to Fig. 1, a punch head 31 is provided which is slidably positioned between two guides 32. Upon the forward movement of the punch head 31, by apparatus to be described later, the

interponents 27 which have been selected and raised to a point adjacent the tape punches 29 will be moved toward the right, as viewed in Fig. 2, resulting in the punches likewise being moved rightwardly. Such a movement of the punches results in perforations being made in the tape, which is not shown in Fig. 2, but is normally passed through the slot 33 just to the right of the end of the punches 29. A guide 34 is provided, inasmuch as the rightward motion of the punches does not stop at the point where it penetrates the tape but passes through the tape a short distance. A comb 36 is also provided having slots therein through which the punches pass. The punches 29 are formed at this point of a smaller section, having shoulders on either side of the comb 36. As the comb is securely connected to the punch head 31 it will move forwardly with the punch head and upon its return movement will engage the rearward shoulder on the punches and cause the punches to be positively withdrawn from the perforations in the tape. The return movement of the punch head 31 is caused by means of the spring 31, which is tensioned during the punching operation and tends to return to its normal position thereafter.

The particular mechanism provided for causing the operation of the punch head 31, resulting in the perforating operation, will now be described. 30 A solenoid 38 is provided which is in an electrical circuit that is established upon the closing of a pair of electrical contacts 101 and 102. These contacts are closed as a result of the depression of the universal T-lever 21 by any of the key levers, which causes a clockwise pivoting, as viewed in Fig. 2, of the lever 22 having the extended lever 26 thereon and the closing of the electrical contact thereby. Referring to Figs. 1 and 6, the upper end of the armature 39 of the solenoid has 40 a bell crank lever 41 attached thereto, the opposite end of which has a slot therein to receive the pin end 42 of an operating lever 43 which is pivoted at 44. The operating lever 43 is normally held in an extreme counterclockwise position, as viewed in Fig. 1, by means of a spring 46 adjustably connected to a lug 47 extending from the operating lever. The operating lever 43 has an upwardly extending lug 48 made integral therewith, through which is adjustably positioned a set screw 49.

Upon the energization of the solenoid 38 as a result of the closing of the electrical contact the armature 39 will be drawn downwardly (Fig. 6) resulting in a pivoting movement of the bell crank lever 41 and a corresponding forward movement of the pin 42 (Fig. 1). Such a movement of the pin 42 causes the operating lever 43 to be moved in a clockwise direction about its pivot point 44, as viewed in Fig. 1, against the tension of its spring 46. The forward movement of the operating lever 43 results in the lug 48 integral therewith likewise moving forwardly, and with the forward end of the set screw 49 coming in contact with the back of the operating punch head 31. A 65 continued clockwise movement of the operating lever 43, which occurs as the armature 39 is moved completely within the solenoid 38, results in the forward movement of the punch head 31 to a point whereat the punch head causes the selected interponents 27 to exert pressure upon the associated punches to perforate the desired code combination in the tape.

Inasmuch as the operator's manipulation of the chosen key is only momentary, the universal 75 T-lever 21 will almost immediately be allowed to

return to its normal position under the action of the spring 24 connected to the associated rearwardly extending lever 22, thereby causing the extending link 26 to move downwardly and break the electrical contact. The opening of the electrical contact results in the de-energization of the solenoid 38, thereby releasing the armature 39 to move upwardly and allowing bell crank 41 to pivot to its normal position under the tension of spring 46 acting on the operating lever 43, causing it to pivot in a counterclockwise direction as viewed in Fig. 1. This latter return movement to normal position is likewise aided by the spring 37 associated with punch head 31, which causes a rearward movement of the punch head.

In the drawings there is illustrated mechanism to impart a variable feed to the tape. However, inasmuch as this mechanism does not form a part of the present invention, nor is it necessary for a complete understanding thereof, it is not being described herein. A full description of this mechanism and its operation may be had by referring to the above-mentioned patent or bulletin.

As previously mentioned, the punch interponents 27 are positioned adjacent to their corresponding punches 29 depending on the interponent selectively conditioned by the mechanical linkage associated with the depressed key lever 11. In prior machines, these interponents will stay in their upward position only for the length of time that the key lever 11 is depressed and will return to their downward position under the tension of the springs 24, immediately upon release of the key lever. Likewise, upon depression of a selected key lever 11, the universal T-lever 21 will be moved downwardly, resulting in an upward movement of the extended arm 26 and a closure of the electrical contact for establishing the solenoid circuit. Upon such condition occurring, the punch head 31 will be moved forwardly, through a mechanical linkage, and pressure applied by the set screw 49 causes the punches 29 to perforate the tape. Because of this latter mechanical linkage for operating the punch head 31, and the relatively slow energization of the solenoid 38, it sometimes happens that the punch interponents 27 will not be in their upward position at the time that the operating punch head 31 moves forward, thereby resulting in the corresponding punch not being operated and a blank code combination being perforated in the tape. For this reason, the apparatus embodied in the present invention has been designed to assure the perforating of the correct code combination by locking the punch interponents in their upward or selected position until the punching operation is insured.

Referring to Fig. 3, it may be seen that each of the punch interponents 27 is provided with a sidewardly extending lug 51 at a point just above their union with the adjustable rods 28. A pair of pawls or latches 52 and 53, having springs 54 which normally tend to bias pawl 52 in a counterclockwise direction and pawl 53 in a clockwise direction, as viewed in Fig. 3, are pivotally positioned in the frame of the apparatus on rods 56. As will be noted, the pawls 52 and 53 are provided toward their upper ends with an inwardly extending lug 57 which is adjacent to and at the same height as the outwardly extending lug 51 of the interponent levers 27. The pawls 52 and 53 are also each provided with a sidewardly extending arm 58 and 59, respectively. As may

be seen in Fig. 5, each of the nineteen punch interponents 27 are provided with a corresponding outwardly extending lug 51 and an adjacent pawl such as 52 or 53. In the normal position 5 of the apparatus, that is, when the key levers are not depressed, the punch interponents 27 are in their downward position and the springs 54 pivot the associated pawls 52 and 53 so that their inwardly extending lugs 57 are in abutment with the adjacent end of the outwardly extending lug 51 of the punch interponents 27.

When one of the punch interponents 27 has been moved to its upward or selected position as a result of the depression of a key lever 11, the lug 51 will move upwardly and out of engagement with the end of the lug 51 of the pawl 52 or 53, thereby allowing the tension of the spring 54 associated with each pawl to pivot the pawl and cause the top surface of the inwardly extending lug 57 to take a position immediately under the outwardly extending lug 51. Thus, upon a release of the interponent 27 any premature tendency for its downward movement will be prevented, inasmuch as the pawl will prevent any downward movement of the interponent 27. It may be seen that all of the nineteen interponents may be locked in their selected positions to insure their being in that position at the time that the punch head 31 advances, and until such time as the pawls will be caused to be pivoted in such a manner that the lugs 51 are free of the lugs 57.

Two baills 61 and 62 are provided, each of which is rotatably mounted on the studs 63. The bail 61 extends transversely of and exerts control over the ten pawls which are associated with the ten interponent levers comprising the control for the lower tier of punches 29, whereas bail 62 extends transversely of and controls the nine pawls which are associated with the nine punch interponents 27 associated with the upper tier of punches 29. It is to be noted that the transverse bail 61 overlies the outwardly extending arms 58 of the pawls 52, while the bail 62 overlies the outwardly extending arms 59 of the pawls 53. The bail 62 has connected to its lower end a connecting link 64 which is mounted at its opposite end on pivot stud 66. The bail 61 is connected to a connecting link 67 through its upwardly extending arm 68 and has its opposite end also pivoted at 66. A lever 69 securely pivoted at 71 extends downwardly from the pivot stud 66 to which its upper end is also pivoted. The lever 69 has a spring 72 secured to its depending arm, the opposite end of the spring being secured to a pin 73 which extends from the frame of the equipment. The lever 69 has an arm 74 extending toward the right, as seen in Fig. 3, which has its inner face in engagement with an eccentric 76. The eccentric 76 is utilized to adjust the normal position of lever 69, and thus links 64 and 67 and baills 61 and 62. The spring 72 tends to rotate the lever 69 in a counterclockwise direction, as seen in Fig. 3, but the previously mentioned engagement between the arm 74 and the eccentric 76 acts as a limit for this counterclockwise motion.

In normal position, the baills, connecting links and arms are in the position shown in Fig. 3 with the baills 61 and 62 being a distance above the outwardly extending arms 58 and 59 of the pawls 52 and 53 and with the spring 72 biasing the lever 69 to its maximum counterclockwise direction whereat the arm 74 engages the eccentric 76. It is to be noted that the arm 74 is

provided with a flat edge 77 just to the left of the pivot stud 66, as seen in Fig. 3.

Referring to Fig. 6, a pin 79 extends downwardly from the bell crank 41, just below its pivot point. A lever 81, Fig. 5, is pivotally mounted at 82 on a bracket extending from the perforating machine and has a slot 83 in one end thereof which cooperates with the pin 79. The opposite end of the lever 81 is formed of a flat upstanding section 84 which has a pair of set screws 85 and 87 secured therein. The utility of set screw 86 will be explained hereinafter. The set screw 87 is positioned immediately adjacent the flat face 77 of the lever 69 which is attached at pivot stud 66 to the links 67 and 64.

In a normal position, or when the solenoid 38 is not energized, the pin 79 assumes the position shown in Fig. 6, toward the left, due to the armature 39 not being drawn within the solenoid and the bell crank 41 pivoting in a clockwise direction. This results in the lever 81 being pivoted in a clockwise direction, as seen in Fig. 5, with the upstanding portion 84 and the set screw 87 being out of engagement with the flat section 77 of the lever 69. When a key lever 11 is depressed, which as previously described causes a contact to close and energize solenoid 38, the solenoid causes the armature 39 to be drawn inwardly resulting in a counterclockwise pivoting of the bell crank 41, as viewed in Fig. 6. This results in the operating lever 43 being pivoted in a clockwise direction, Fig. 1, resulting in the operating head 31 engaging the upper ends of the punch interponents 27 and causing the punches 29 to perforate the tape. At the same time that the bell crank lever 41 was pivoted in a counterclockwise direction, Fig. 6, due to the energization of solenoid 38, the pin 79 caused the lever 81 to be pivoted in a counterclockwise direction, as viewed in Fig. 5, resulting in the set screw 87 coming into engagement with the flat surface 77 of the lever 69 and thus pivoting the lever 69 in a clockwise direction, as viewed in Fig. 3. A clockwise movement of the lever 69 causes the links 67 and 64 to be moved toward the right, as viewed in Fig. 3. As previously mentioned, link 64 is pivotally connected to bail 62, and link 67 is pivotally connected to bail 61 by the arm 68. The rightward movement of the link 64 results in the bail 62 being pivoted in a counterclockwise direction, as seen in Fig. 3, causing its transverse section to come in contact with the upper surface of the outwardly extending arms 59 of the pawls 53. At the same time, the rightward movement of the link 67, through the arm 68 causes the bail 61 to be pivoted in a clockwise direction, Fig. 3, causing its transverse section to engage the upper surface of the outwardly extending arms 58 of the pawls 52. Thus, both the pawls 52 and 53 will be caused to pivot about their pivots 56, against the tension of their respective springs 54. Such a pivoting of the pawls results in their inwardly extending lugs 57 being moved outwardly thus freeing the outwardly extending lugs 51 of the punch interponents 27. Thus, at this time, the punch interponents are able to return to their normal or extreme downward position in readiness for another key to be depressed.

Inasmuch as the bell crank lever 41 controls the operation of the punch head 31 through the operating lever 43, and the operation of the release of the bails through the linkage and the lever 81, it is necessary that the set screw 87 be positioned in such a manner that it will not come in engagement with the flat surface 77 of

the lever 69 and cause the lever 69 through the links 64 and 67 to release the punch interponents 27 by means of the pawls 52 and 53, until such time as the operating head 31 has moved forwardly to an extent necessary to come in contact with the top end of the punch interponents 27 and cause the code combination to be perforated in the tape. This is possible inasmuch as the punches do not stop immediately upon contact with the tape, but instead pass through it a short distance. In this manner it is assured that the punch interponents will not be allowed to move downwardly as they are positively engaged by the head 31 in the actual tape perforating operation. When the punch head 31 is free to resume its normal or outward position due to the de-energization of solenoid 38 the punch interponents 27 are free to resume their normal or downward position.

An operational view has been shown in Fig. 4 wherein the pawls are shown in solid lines in their locking or latching position beneath the outwardly extending lugs of the punch interponents, and the pawls are shown in dotted lines in their position of release with respect to the outwardly extending lugs of the punch interponents after the action of their respective bails. The corresponding two positions of the links connected to the bails, the lever 69 and the set screw 87, and the upwardly extending section 84 of the lever 81 have all been shown. It is to be remembered that the normal position is not in a latched but rather in an unlatched position.

Fig. 7 discloses a device which is designed to insure that the electrical contact associated with the universal T-lever 21 will be held in its closed position for a time sufficient to allow the solenoid 38 to be completely energized. As disclosed in Fig. 6, the lever 26 forming an extension of the rearwardly extending lever 22 associated with the universal T-lever 21 has a sidewardly extending ear 91 which has a set screw 92 adjustably positioned therein. A bar 93 is slidably mounted on the frame of the perforating machine by slots 94 in bar 93 which travel on pins 95 extending from the frame. The bar 93 has a sidewardly extending lug 96 which has a spring 97 secured thereto. The opposite end of the spring 97 is secured to a lug extending from the frame to which the bar 93 is slidably mounted, the spring normally tending to urge the bar 93 to its downward position. The bar 93 is also provided with an outwardly extending lug 98 and an upwardly and inwardly extending insulated lug 99. The utility of these latter two lugs will be mentioned hereinafter. The electrical contact which has previously been mentioned as being under the control of the universal T-lever 21 is formed of an upper spring contact member 101 and a lower spring contact member 102. During the normal or unoperated position of these spring contacts 101 and 102 their normal resilience urges them in a direction opposite to each other so that at this time the electrical contact is in its open position with no circuit established for the energization of the solenoid 38.

A three-armed lever is pivoted at 103 on a post extending from the upright frame work of the apparatus, having one arm extending downwardly with a hook 106 at its lower extremity. A second arm 107 extends sidewardly, as seen in Fig. 6, and has a spring 108 attached toward its outer end, the spring tending to pivot the three-armed lever in a clockwise direction. A third arm 109 extends upwardly above the pivot point 103 and

has a flat round lug 114 (Fig. 7) at the top thereof. It is to be noted that the hook 106 on the arm 104 is adjacent to the sidewardly extending lug 98 of the bar 93, and the circular top section 111 of the arm 109 is adjacent to the set screw 86, previously mentioned, which is secured in the upwardly extending section 84 of the lever 81.

A second three-armed lever is pivoted at 110 to a post extending from the frame, and comprises an arm 112 extending toward the left, as seen in Fig. 6, which has a small bulge on its lower surface at a point immediately overlying the upper electrical spring contact 101, and a rounded outer extremity. The rounded outward end of the arm 112 overlies a stop 113 connected to the frame. A second arm 114 extends toward the right, as viewed in Fig. 6, and has the opposite end of the spring 108, the other end of which was secured to arm 107 of the first mentioned three-armed lever, secured to its outer extremity. A third arm 116 extends upwardly and is provided with a set screw 117 passing therethrough, which in its normal position is situated immediately to the rear of the upturned section 84 of the lever 81.

When any one of the individual key levers 11 is depressed, the universal T-lever 21 is likewise depressed, as previously mentioned, resulting in a pivoting movement of its rearwardly extending lever 22 having the extending link 26 connected thereto. As viewed in Fig. 6, this results in a counterclockwise movement of the extending link 26. Any such movement to this link is imparted to its sidewardly extending portion 91, and the set screw 92 therein is likewise moved in a counterclockwise direction, resulting in the set screw 92 engaging the bottom of bar 93 and urging it upwardly against the tension of the spring 97. An upward movement of the bar 93 causes the lower spring contact 102 to be moved upwardly, inasmuch as this contact spring is immediately above the bar 93. Inasmuch as the lug 98 is a part of the bar 93, it will also move upwardly, thus allowing the arm 104 of the three-armed lever pivoted at 103 to move in a clockwise direction under the tension of the spring 108 thereby causing the hook 106 at the lower end of the arm 104 to move to a position underlying the lug 98 which has just moved upwardly. During this upward movement the lower electrical contact 102 has been caused to engage the upper electrical contact 101 and inasmuch as the bar 93 moves to an extent slightly higher than that necessary for the hook 106 to underlie the lug 98, the two contacts must be held in engagement with each other. As a matter of fact, the top spring contact 101 is positively kept in engagement with the lower spring contact 102 by means of the arm 112 of the three-armed lever pivoted at 110 which has, as previously mentioned, a bulge in its lower surface immediately above the upper contact spring 101. The arm 112 is normally biased in a counterclockwise direction, as viewed in Fig. 6, by the spring 108. During the slight amount of downward movement of the bar 93, after the universal T-lever 21 and the rearwardly extending lever 22 and the connecting link 26 are released, to the point whereat the lug 98 will engage the hook 106 and hold the bar 93 in an upward position, the two contacts are kept in engagement by means of the tension of the spring 108 urging the arm 112 in a counterclockwise direction. Thus, by this device it is insured that the electrical contacts will be positively closed and that by the lock-up arrangement they will be kept in engagement for

a sufficient length of time. This latter feature is important inasmuch as the establishment of the electrical circuit for the energization of solenoid 38 depends on this electrical contact.

It will be remembered, as previously described, that upon the energization of solenoid 38 causing the armature 39 to move downwardly, as viewed in Fig. 6, and resulting in a counterclockwise movement of bell crank 41, that the lever 81 will be pivoted in a counterclockwise direction, as viewed in Fig. 7. Upon the counterclockwise movement of the lever 81, the set screw 86 passing through its upwardly extending section 84 will engage the rounded upper extremity 111 of the arm 109 of the three-armed lever pivoted at 103, causing arm 109 to pivot in a counterclockwise direction (Fig. 6). Such a movement of the arm 104 results in the hook 106 at its lower extremity moving outwardly and freeing the sidewardly extending lug 98 of the bar 93. At this time, the bar 93 is free to move in a downward direction under tension of its spring 97, inasmuch as the set screw 92 immediately underlying the bar 93 has also been moved. Upon the downward movement of the bar 93 its upwardly and sidewardly extending lug 99, which overlies the lower spring contact 102, causes this contact to be moved in a downward direction thereby insuring an opening of the electrical contacts. At the same time as the arm 104 pivots in a counterclockwise direction, as viewed in Fig. 6, the spring 108 extending from arm 107 will tend to exert a pressure on the arm 114 of the three-armed lever pivoted at 110 attempting to move the arm 112 in a counterclockwise direction, as viewed in Fig. 6. If this were to occur, the arm 112 would cause the spring contact 101 to follow the other spring contact 102 downwardly, resulting in the contact being kept closed rather than opened. However, the stop 113 prevents the arm 112 from moving further than a predetermined distance.

After the electrical contacts have been opened the solenoid 38 is de-energized and the armature 39 released thereby, resulting in the bell crank lever 41 being pivoted in a clockwise direction, as viewed in Fig. 6. Such a movement of the bell crank lever 41 results in a similar movement to the pin 19 connected thereto, resulting in the lever 81 being pivoted in a clockwise direction, as viewed in Fig. 7. As the lever 81 moves in this direction its upturned section 84 engages the set screw 117 which passes through the arm 116 of the three-armed lever pivoted at 110. Upon further movement of the lever 81 the arm 116 is urged in a counterclockwise direction, as viewed in Fig. 7, resulting in the second arm 112 likewise moving in a counterclockwise direction and thereby releasing pressure from the upper spring contact 101 which it overlies. Inasmuch as at this time no pressure is being applied to either the upper spring contact 101 or the lower spring contact 102 they will be allowed to respond to their inherent resilience which results in their being urged in opposite directions, thereby insuring that the electrical contact will remain open.

The various set screws utilized in this device have been provided so that adjustments may be made, thereby insuring that the proper timing occurs between the various operations.

Although a specific embodiment of the invention has been shown and described, it will be understood that this embodiment is but illustrative and that various modifications may be made therein without departing from the scope and spirit of the invention.

- What is claimed is:
1. In combination in a perforating machine, a plurality of punches, a plurality of punch controllers, one individual to each of said punches, a keyboard selector mechanism for selectively setting said controllers in various combinations, means for moving said selected controllers to cause said punches to perforate a tape, a separate spring urged pawl individual to each of said controllers, a lug extending from each of said controllers whereby when such controllers are in their selected positions said spring urged pawl will assume a position beneath said lug to block said controller in its selected position, and means to release said spring urged pawls from blocking engagement with said lug to allow said controllers to assume their unselected position.
  2. In a perforating machine, a key actuated selector, a plurality of punches, a plurality of punch interponents, one individual to each of said punches, said interponents selectively conditioned by said selector in various combinations, a return spring for each of said interponents, means for moving said conditioned punch interponents to cause said punches to perforate a tape, separate means to directly latch said interponents in their conditioned position, and means under the control of said punch interponent moving means to restore said latching means whereby said punch interponents may be returned by their said springs to their nonconditioned positions.
  3. In a keyboard perforator, a plurality of punches, a plurality of interponents, one individual to each of said punches, key lever means for selectively conditioning said interponents in various combinations, means for moving said conditioned interponents to cause said punches to perforate a tape, separate latch means cooperable directly with each of said interponents for holding said interponents in their said selected positions after said key lever means are released, and means under the control of said means for moving said interponents for releasing said interponents from their said selected positions.
  4. In a keyboard perforator, a plurality of punches, a plurality of interponents, one individual to each of said punches, key lever means for selectively conditioning said interponents, a punch hammer for moving said conditioned interponents to cause said punches to perforate a tape, latch means cooperable directly with each of said interponents for holding said interponents in their selected positions after said key lever means are released, and release means including a pair of bails for restoring said latch means whereby said interponents are free to resume their nonselected positions.
  5. In a keyboard perforator, a plurality of punches, a plurality of interponents, one individual to each of said punches, key lever means for selectively conditioning said interponents in various combinations, a solenoid energized upon the operation of said key lever means, a punch hammer under the control of said solenoid for moving said conditioned interponents to cause said punches to perforate a tape upon the energization of said solenoid, separate latch means cooperable directly with each of said interponents for holding said interponents in their selected positions after said key lever means are released, and means under the control of said solenoid for releasing said latch means whereby

said interponents are released from their said selected positions.

6. In combination in a perforating machine, a plurality of punches, a plurality of punch interponents, one individual to each of said punches, a keyboard selector mechanism for selectively setting said interponents in various combinations, means for moving said selected interponents to cause said punches to perforate a tape, separate blocking means individual to each of said interponents, a lug extending from each of said interponents whereby when said interponents are in their selected positions said blocking means will assume a position beneath said lugs to block said interponents in their selected position, and means to release said blocking means from its blocking engagement with said lug to allow said interponents to assume their unselected positions.
7. In combination in a perforating machine, a plurality of punches, a plurality of punch interponents, one individual to each of said punches, a keyboard selector mechanism for selectively setting said interponents in various combinations, means for moving said selected interponents to cause said punches to perforate a tape, a separate spring urged pawl individual to each of said interponents, a lug extending from each of said interponents whereby when said interponents are in their selected position said spring urged pawls will assume a position beneath said lugs to block said interponents in their selected position, and means under the control of said means for moving said selected interponents to release said spring urged pawls from their blocking engagement with said lugs to allow said interponents to assume their unselected positions.
8. In combination in a perforating machine, a plurality of punches, a plurality of punch controllers, one individual to each of said punches, a keyboard selector mechanism for selectively setting said controllers in various combinations, means for moving said selected controllers to cause said punches to perforate a tape, separate blocking means individual to each of said controllers, means forming a part of said controllers whereby when said controllers are in their selected position said blocking means will engage said means forming a part of said controllers to block said controllers in their selected positions, and means to release said blocking means from its blocking engagement with said means forming a part of said controllers to allow said controllers to assume their unselected positions.
9. In combination in a perforating machine, a plurality of punches, a plurality of punch controllers, one individual to each of said punches, a keyboard selector mechanism for selectively setting said controllers, means for moving said selected controllers to cause said punches to perforate a tape, a spring urged pawl individual to each of said controllers, a lug extending from each of said controllers whereby when said controllers are in their selected positions said spring urged pawls will assume a position beneath said lugs to block said controllers in their selected positions, and means including a pair of bails under the control of said means for moving said selected controllers to release said spring urged pawls from their blocking engagement with said lugs to allow said controllers to assume their unselected positions.
